ROTARY CARD INDEX AND TRAY

Karl H. Miller, North Canton, Ohio, assignor to
Diebold, Incorporated, Canton, Ohio, a corpora-
tion of Ohio

Application September 8, 1943, Serial No. 501,567

1 Claim. . (Cl. 129—16)

1

The invention relates to a rotary card index or tray in which cards are mounted on a preferably circular carrying-rail or a section thereof.

Thus, in Bruen Patents Nos. 2,168,323 and 2,235,736, cards are mounted on a peripheral carrying-rail which is composed of a plurality of arcuate sections detachably mounted on a wheel. Also, a card carrying-rail section may be detachably mounted on a desk tray as shown in Bruen Patent No. 2,240,325. Moreover, the card carrying-rail section, although shown in said patents as being detachable, may be formed as an integral part of a tray or wheel section.

In any of such constructions, the cards are mounted on one or more carrying-rails, each of which has a keyhole shape in cross section by engaging each rail head within a keyhole slot or aperture formed in the bottom of each card.

Heretofore, such carrying-rails, because of their complicated shape particularly when they are arcuate sections, have been made of die cast metal. After the usual semi-finishing operations to make the surfaces thereof as smooth as possible, the sections are plated with copper and finally with chromium to provide a smooth surface so that the cards mounted thereon will readily slide back and forth along the rail head.

However, difficulty has been experienced in obtaining the necessary metal for the manufacture of such rail sections, and their manufacture has been relatively expensive because of the character of material and operations involved.

Moreover, detachable segment bars or rail sections, when mounted on a wheel or on a tray, are held on pins, and it has been found necessary to hand file the pin engaging slots in each segment bar in order that the segment bars may be interchangeable on the periphery of the mounting wheel.

This difficulty arises, due to the practical impossibility of exactly locating the spacing distance between each set of pins around the periphery of the wheel when a plurality of sets of pins are used for mounting a plurality of segment bars or rail sections.

The greatest difficulty, however, which occurs in the use of the described prior constructions, is that the cards which are mounted on the rail heads, in continually sliding back and forth along the rail heads in use, and which cards are usually made of flat, stiff, paper or cardboard, may wear at the edges of the keyhole slot therein and may result in fraying or feathering of the edge of the keyhole slot. In other words, the contact surface between the cards and rails must be

2

perfectly smooth and entirely free of pits or roughness in order to avoid such wear.

Moreover, the continual sliding action of the cards back and forth along the rail head may 5 wear away the plated surface on the rail head so as to roughen the same and ultimately expose the die cast metal, which is considerably rougher than the plated metal surface thereon. If the plated metal wears away or corrodes and if the surface 10 of the rail head becomes rougher, it in turn may cause a faster wearing away of the keyhole slot edge of the card. Therefore the cards sometimes become so worn that they are not retained on the rail head and must be replaced. In other 15 words, considerable care and expense is involved to assure a smooth rail contact and to eliminate wear.

Finally, the sliding of the cards back and forth on the metal rail section during the constant use and movement of a rotary card index is noisy. 20 Moreover, the mounting of the rail sections on the pins of the carrying wheel may give a clicking noise during movement of the wheel unless the engagement between the pins and slots in the rail segment is perfect; and this ordinarily is not the 25 case because of the tolerances which must be maintained for interchangeability.

It is therefore an object of the present invention to provide a rotary card index or tray carrying-rail construction, which is cheaper to make 30 than the present metal construction thereof.

Furthermore, it is an object of the present invention to provide a rotary card index and tray carrying-rail construction, which eliminates the use of critical die cast and plating metals.

35 Also, it is an object of the present invention to provide a rotary card index and tray carrying-rail construction which is quieter in operation with cards mounted thereon than when metal carrying-rails are used.

40 Finally, it is a paramount object of the present invention to provide a rotary card index and tray carrying-rail construction, which substantially reduces the wear and fraying on cards mounted thereon.

45 I have discovered that the wearing action of the cards upon the metal rails and of the rails upon the cards may be materially reduced by forming the rail of molded plastic material. I have unexpectedly discovered that in actual use, 50 the continued sliding of the cards back and forth along a carrying-rail formed of plastic material, has a smoothing or polishing action upon the surface of the plastic material rail head, so that it becomes smoother and smoother and the wear 55 upon the cards is less and less.

Moreover, I have discovered that it is not necessary to polish or finish the molded plastic surface of a plastic rail section in any way, except for buffing off the fin at the mold parting line, because of the smoothing, polishing or finishing action of the cards upon the rail during use thereof.

Also, a plastic carrying-rail section or segment bar is much cheaper to manufacture than one of metal, and the operation of the cards thereon is much quieter than on a metal rail. Moreover, the plastic rail sections are lighter in weight than metal rail sections and therefore reduce the work expended by and fatigue of the operator or user of the rotary or tray index. These are very valuable advantages in the very extensive and constantly increasing use of rotary and tray card indexes.

Many of the myriad kinds of available moldable thermoplastic materials may be used. I have found that a cellulose-acetate-butyrate plastic material is very satisfactory. The thermoplastic material should have medium hardness or brittleness so as to give some flexibility. It must not be so hard or brittle that it cracks or breaks when the card load thereon is shifted and results in shock as a wheel rotates. On the other hand, it must not be so soft that the surface thereof wears away due to the sliding of cards back and forth thereover, or that the pin mounting engaging slots wear or pound or distort out of shape.

Moreover, I have also discovered that the flexibility and elasticity of thermoplastic material which has a medium hardness or brittleness, is sufficient to enable rail sections thereof, as molded, to be used interchangeably on the periphery of the wheel without regard to small differences in the spacing of the pins upon which they are mounted. This characteristic not only eliminates the necessity of hand filing or fitting the rail sections, but also enables the rail sections to hold tight on the pins and eliminates the clicking noise which has been due to looseness in the metal pin and metal slot mounting thereof.

Accordingly, it is a further object of the present invention to provide a rotary card index or tray with a carrying-rail formed of molded thermoplastic material with cards mounted thereon to overcome the described prior art difficulties, and to obtain the new results set forth and the advantages of the discoveries enumerated.

These and other objects may be obtained, the stated results achieved, and the described difficulties overcome, by the devices, constructions, arrangements, combinations, parts, and elements which comprise the present invention, the nature of which is set forth in the following general statement, preferred embodiments of which are set forth in the following description, and are shown in the drawings, and which are particularly and distinctly pointed out and set forth in the appended claim forming part hereof.

The nature of the improvements in rotary card indexes and trays of the present invention may be stated in general terms as preferably including in a card filing device a rail section preferably comprising a head and a flange constructed and arranged to receive a multiplicity of cards having keyhole-shaped slots at their lower edges, constructing the rail section of molded thermoplastic material, and mounting cards thereon with their keyhole-shaped slots embracing the rail and flange.

By way of example, preferred embodiments of

the improved construction are illustrated in the accompanying drawings forming part hereof, wherein:

5 Figure 1 is a side elevation of the upper segment of a card index wheel with arcuate sections of a card carrying rail mounted thereon;

10 Fig. 2 is a section taken on the line 2—2, of Fig. 1;

Fig. 3 is a similar section taken on the line 3—3 of Fig. 1;

15 Fig. 4 is a perspective view of a desk tray with a removable arcuate rail section therein;

Fig. 5 is a perspective view of a removable arcuate rail section such as used in the devices of Figs. 1 to 4, showing a number of cards carried thereon;

20 Fig. 6 is a view similar to Fig. 4, but showing a tray with an integral rail section;

Fig. 7 is a fragmentary view of the lower portion of the card with a keyhole slot engaging the head of a rail section; and

25 Fig. 8 is a fragmentary view of a card showing a round aperture engaged upon a round rod.

Similar numerals refer to similar parts throughout the drawings.

Figs. 1, 2 and 3 show the segment 10 of the rim of a card index wheel, composed of two halves secured together by bolts 11, with a slot 12 for receiving the flange 13 of an arcuate rail section 20, and the rail having the head 14 upon which the keyhole slot 15 in the lower edge of the card 16 may be engaged and upon which the card may slide along the rail.

One end of each rail flange 13 is provided with 35 a slot 13a adapted to engage with one of the bolts 11, and the other end of rail flange 13 is provided with an aperture 13b which is adapted to be engaged by a locking latch 17 when the rail flange 13 is mounted in slot 12 of the wheel rim.

40 Another slot 13c is formed in the rail flange 13 adjacent aperture 13b for engaging pin 18 also carried by the rim of the card index wheel. Thus, bolts 11 and pins 18 engaging in slots 13a and 13c locate, support and position the arcuate rail sections 20 on the periphery of the card index wheel 10.

Any arcuate rail section 20, with or without cards thereon, may be removed from the rim of the wheel 10 by disengaging the latch 17, as shown 50 by broken lines in Fig. 1, and the arcuate rail section 20, with (as in Fig. 5) or without cards thereon, can be mounted in a tray 19, as shown in Fig. 4, for inspecting and working with and on cards mounted on the rail 20.

55 The tray 19 illustrated in Fig. 4, is provided with a slot 21 for receiving flange 13 of rail section 20, and pins (not shown) are also carried by tray 19 for engagement with slots 13a and 13c of rail section 20 to position the same on the tray.

60 A latch 22 may also be provided on tray 19 for engagement with aperture 13b to releasably lock rail section 20 on the tray 19.

As described, tray 19 is adapted for coordinated use as a desk tray in connection with use of the 65 wheel type index illustrated in Fig. 1. However, it is to be understood that desk trays such as illustrated at 19 in Fig. 4, equipped with arcuate rail sections 20, may be used as desk card files.

Alternately, a desk card file of the tray type 70 such as illustrated in Fig. 6, may be used in which the rail portion 20b is integral with the tray portion 19a. In such a construction, the forward end wall 23 is formed integral with the tray portion 19a, while the rear end wall 24 is preferably 75 pivotally mounted at 25 on the tray portion 19a

5

so as to provide a stop for cards mounted on the rail 20b. The pivotal mounting 25 may be a spring type hinge normally urging the wall 24 to the position shown, but permitting its movement backward for placement or removal of cards.

Although the invention has been illustrated and described with reference to an arcuate rail having a flange 13 and a head 14, the improvements may be incorporated in an index or tray construction having a straight rail as distinguished from an arcuate rail, or in a construction having a round rail 14a, as indicated in Fig. 8.

In accordance with the present invention, the rail section, whether arcuate or straight, whether keyhole-shape or round in cross section, and whether detachably or integrally supported is formed of a moldable thermoplastic material, such as cellulose-acetate-butylate plastic material. The usual cards are engaged with and removed from the rail in the usual manner and may continually slide back and forth along the rail head formed of molded thermoplastic material without fraying or tearing the contacting edges of the keyhole slot 15 of the cards 16 because the sliding contact of the cards on a rail formed of molded thermoplastic material makes the surface of the rail smoother and smoother in use and decreases wear on the cards.

Moreover, the flexibility and elasticity of the thermoplastic material enables arcuate rail sections 20 to be detachably and interchangeably used in various positions on the wheel, such as shown in Fig. 1, or on various trays such as shown in Fig. 4, without specially fitting the slots 13a and 13c with respect to the location of the bolts 11 and pins 18. That is to say, the flexibility and elasticity of the thermoplastic material permits the section 20 to spring into supported and held position and to be there tightly supported and held by the bolts 11 and pins 18, even though there may be an inaccurate spacing of the bolts 11 and pins 18.

This arrangement also eliminates a clicking noise which frequently occurs when a card index wheel is rotated, due to looseness in the pin and slot support for mounting metal rail sections 20 on a wheel.

Moreover, the sliding movement of the cards back and forth along a rail formed of thermoplastic material during operation and use of the wheel is much quieter than when the rail is formed of metal and the manufacture of rail sections from molded thermoplastic material is much cheaper.

Accordingly, the present invention provides for the manufacture of molded thermoplastic mate-

6

rial carrying-rails for tray or rotary card indexes which are much cheaper than the present metal construction thereof, which eliminates the use of critical die cast and plating metals, which construction is quieter with cards in operation thereon than when metal carrying-rails are used, and which molded thermoplastic material rail construction with cards thereon substantially reduces wear on the cards.

10 The embodiments of the present improvements illustrated and described herein are by way of example, and the scope of the present invention is not limited to the exact details of construction of the various parts. When the term "rail" 15 is used herein and in the appended claims, that term is used in its broadest sense, irrespective of the character of its cross section.

Having now described the features of the invention, the construction, operation and use of preferred embodiments thereof, and the advantageous new and unexpected results attained by the improved construction; the new and useful parts, elements, combinations, constructions and devices, and reasonable mechanical equivalents 20 obvious to those skilled in the art, are set forth 25 in the appended claim.

I claim:

30 In a card index and the like, the combination of a molded thermoplastic rail section comprising a head and a flange constructed and arranged to receive a multiplicity of paper cards having keyhole-shaped slots at their lower edges to embrace the rail head and flange to mount the cards for sliding movement to and fro along the rail, a support, spaced sets of pins carried by the support, and the flange being provided with slots engageable selectively with a set of said pins, where- 35 by the flexibility and elasticity of the thermoplastic rail section enables the rail section to be 40 interchangeable and tightly supported by any set of pins without specially fitting the slots with each set of pins.

KARL H. MILLER.
